UNITED STATES PATENT OFFICE

2,571,534

WINDOW ALARM

James W. Brooks, Knoxville, Tenn.

Application January 20, 1950, Serial No. 139,569

3 Claims. (Cl. 200—54)

1

This invention relates to a window alarm, and more particularly to an alarm device for attachment to a window frame having a protective window guard for indicating, by an audible or visible alarm, that the window guard is being tampered with.

It is an object of this invention to provide a window guard of the kind to be more particularly described hereinafter having a window guard frame to be supported on the window frame by an alarm switch, the switch to be closed for energizing an alarm circuit upon displacement of the guard frame in any direction by an unauthorized person.

Another object of this invention is to provide a window guard of this kind having a switch with a movable contact to be engaged with one of a plurality of fixed contacts for closing an alarm circuit upon movement of a guard frame suspended from the movable contact member.

Still another object of this invention is to provide an electric switch for an alarm circuit of this kind, the electric switch being adapted to be closed upon movement of the movable contact member in a vertical or horizontal direction.

A further object of this invention is to provide a burglar alarm of this kind which is compact in nature, simple in structure, and adapted to be manufactured and distributed at a low price for use in places where a plurality of such circuits is desired to be used.

With the above and other objects in view, my invention consists in the arrangement, combination and details of construction disclosed in the drawings and specification, and then more particularly pointed out in the appended claims.

In the drawings:

Figure 1 is a front elevation of the window having a window alarm of this kind, the drawing showing the alarm circuit in diagrammatic form;

Figure 2 is a front elevation, partly broken away, of the switch member used in the alarm;

Figure 3 is a vertical, transverse section taken on the line 3—3 of Figure 2;

Figure 4 is a vertical, longitudinal section taken on the line 4—4 of Figure 3;

Figure 5 is a top plan view, partly broken away, of the switch elements broken away from the alarm circuit and window guard frame; Figure 5 being substantially a top plan view of Figure 2.

Referring to the drawings, the numeral 10 designates generally a window frame, or frame about any other opening, on which a window

2

alarm 11, constructed according to an embodiment of my invention, may be employed.

The alarm 11 comprises a window-closing guard frame 12 to be supported on an electric switch 14 which is connected in an alarm circuit 15 including an audible alarm member, such as a bell 16. While an audible alarm, as the bell 16, is shown in the drawings, it is to be understood that any other type of alarm device, such as an alarm light or the like, may be used.

The guard frame 12 comprises a pair of transversely spaced apart, vertically extending frame members 17 and 18 which are connected together by a plurality of transverse frame members or bars 19. The vertically extending side frame members 17 and 18 are adapted to overlie the side portions or members of the window frame 10, while the transversely extending frame members 19 are adapted to extend across the opening which is to be covered, or protected, by the window guard frame 12. The uppermost of the transversely extending guard frame members, the member 20 as noted in the drawings, is adapted to be extended at its opposite ends outwardly 25 beyond the side frame members 17 and 18, as clearly noted in Figure 1 of the drawings.

An alarm switch 14 is adapted to be fixedly secured to the window frame 10 at the opposite upper corners thereof, as clearly noted in Figure 30 1 of the drawings, the guard frame 12 to be suspended from the switches 14 in the manner to be more particularly described hereinafter.

Each of the switches 14 is formed with a body or casing 21 formed of wood, plastic, or other suitable insulated material formed to any suitable shape, the casing 21 being adapted to be secured by any suitable fastening means, not shown in the drawings, to the surface of the window frame 10. Each of the switches 14 is formed 40 in the same manner, and therefore it is submitted that a detailed description of one of the switches 14 may be suitably applied to the other of the switches 14.

The insulated casing 21 is provided with a vertically extending bore 22 opening through the upper and lower ends thereof, as clearly noted in Figure 4 of the drawings. A longitudinally extending recess 24 is formed on the upper side of the casing 21 and opens at one end into the bore 22.

A transverse hinge or pivot pin 25 is fixedly secured in the casing 20 within the recess 24 remote from the bore 22. A movable contactor member 26 is mounted on the pivot pin 25 for engagement with a fixed contact upon actuation or

inadvertent movement of the window guard frame 12.

The movable contactor member 26 includes a substantially horizontally extending arm 27 pivoted at one end on the pivot pin 25, the other end of the horizontal arm 27 extending into the upper end of the bore 22. A substantially vertically extending arm 28 is pivotally mounted by the hinge pin 29 on the end of the arm 27 within the bore 22, clearly noted in Figure 4 of the drawings, the vertically extending arm 28 depending from the lower end of the bore 22. The lower end of the depending arm 28 is formed in the manner of an eye or hook 29 for receiving one end of the outwardly extending, transverse, upper bar 20 of the window guard frame 12. The engagement of the outwardly extending pintle members 30 on the opposite ends of the upper transverse bar 20 through the hooks or eyes 29 substantially suspend the window guard frame 12 from the depending, vertically extending, movable contactor member 26.

A pair of transversely extending vertically spaced fixed contacts 31 and 32 are fixedly secured within the casing 21 adjacent the end of the horizontally extending contact arm 27 adjacent the vertically extending bore 22. The upper, fixed contact member 31 is adapted to be engaged by the upper surface of the horizontally extending arm 27 of the movable contactor 26, the fixed contact member 31 constituting an abutment member for limiting the upward swinging of the movable contactor member. The lower, fixed contact member 32 is adapted to be engaged by the lower edge of the longitudinally extending arm 27 of the movable contactor member 26 for limiting the downward swinging movement of the contactor member 26, as biased downwardly by the weight of the window guard frame 12.

A central, upwardly opening recess 34 is formed in the center of the housing 21, the upper end of the counterbore or recess 34 opening into the lower side of the recess 24 in which the movable contact 26 is mounted. A spring 35 abuts at its lower end on the casing 21, the spring 35 being engaged in the recess 34, and the upper end of the spring 35 engages the lower edge of the horizontally extending arm 27 of the movable contact member 26 for constantly biasing the movable contact member 26 upwardly against the weight of the guard frame 12. Under normal conditions, the spring 35 will exactly balance the weight of the window guard frame 12 so that the horizontally extending, movable contact arm 27 will be positioned between the vertically spaced apart fixed contacts 31 and 32, as clearly noted in Figure 4 of the drawings.

An annular, fixed contact 36 is mounted on the lower end of the bore 22, the fixed contact 36 being disposed concentric to the axis of the bore 22, whereby the depending arm 28 of the movable contact member 26 may be suspended from its pivot 29 out of engagement with the inner edge of the annular contact 36 in the normal position of the window guard frame 12.

The electric circuit 15 comprises a wire 37 which is connected between the fixed contacts 31, 32 and 36 and one side of the alarm member 16. Another wire 38 is connected between the pivot pin 26 of the movable contactor arm 27 and one side of the battery 39, or other source of electrical power for the circuit 15. A wire 40 is connected between the other side of the battery 39 and the remaining side of the alarm member 16, a main or master switch 41 being connected in the wire

40. Where a switch 14 is used on the opposite sides of the window frame 10, a common connector member 42 is connected between the fixed contact members of the respective switches 14, so that closing of either one of the switches 14 will complete or close the circuit to the same alarm member 16 in the manner clearly noted in Figure 1 of the drawings.

In the use and operation of the window alarm described above, the window alarm frame 12 will normally be suspended from the depending arm 28 for free swinging movement therefrom, the vertical contact arm 28 being positioned out of engagement with the annular contact 36, and the horizontally positioned, movable contactor arm 27 being normally positioned between the vertically spaced apart, fixed contacts 31 and 32 in the manner clearly shown in Figure 4 of the drawings. When the window guard frame 12 is balanced by the spring 35 in intermediate position, the movable contactor member 26 is out of engagement with the fixed contacts 31, 32 and 36, the alarm circuit 15 is in a sensitive condition, the master switch 41 being in closed position. Upon any movement of the guard frame 12, the alarm circuit 15 will be closed for actuating the alarm member 16. It will be noted that upon raising the frame 12, the movable contactor arm 27 will engage the upper, fixed contact 31 and upon downward movement of the frame 12, the movable contactor arm 27 will engage the lower, fixed contact 32. Upon any swinging movement of the window guard frame 12, the vertically extending, movable contactor arm 28 will engage the annular, fixed contact 36.

As the house wiring circuit is also a vulnerable point which is frequently broken, as by cutting or other circuit disconnecting means, by a person desiring unlawful entry to a home or other dwelling which may be protected by electric burglar alarms, I have provided a switch 50 adapted to be connected in parallel with the alarm circuit 15 for sounding the alarm 16 upon breaking the main electric circuit 51 of the dwelling.

The switch 50 includes an armature 52 pivoted at one end on a pivot pin 54 and connected to a wire 55, which, in turn, is connected to the wire 38 of the alarm circuit 15 between the battery 39 and alarm 16. The other contact 56 of the switch 50 is connected by the wire 57 to the wire 37 on the other side of the alarm 16 in such a manner that when the armature 52 is in engagement with the other contact 56, the alarm circuit will be closed for actuating the alarm 16 in the same manner as when the circuit is closed by the switch 14 described above.

The armature 52 will normally be biased to a switch opening position by a spring 58, by gravity or other suitable biasing means. An electromagnet 59 is connected to the main house circuit 51 at a point to be actuated at all times until the entrance or main wire connections to the house are broken. The electromagnet 59, when actuated by the house circuit 51 will rock the armature 52 out of engagement with the contact 56 to open the switch 50 and consequently the alarm circuit 15. The electromagnet 59 operates in opposition to the spring 58, or other biasing means acting on the armature so that upon failure of the main circuit 51 the alarm circuit will be closed.

While the main power alarm switch 50 is shown in the drawings as being connected in the same alarm circuit as the window alarm switch 14, it

is to be understood that the power alarm switch may be connected on a separate alarm circuit or in combination with another alarm switch which is normally open.

I do not mean to confine myself to the exact details of construction herein disclosed, but claim all variations falling within the purview of the appended claims.

I claim:

1. In a switch, an insulated body, a generally horizontal contactor arm pivoted at one end on said body and having a free end, a generally perpendicular contactor arm pivoted at its upper end on the free end of said horizontal contactor arm, upper and lower fixed contacts on said body located above and below said horizontal contactor arm, resilient means acting between said body and said horizontal contactor arm serving to normally position said horizontal contactor arm in an intermediate position wherein said horizontal contactor arm is vertically spaced from and out of contact with said upper and lower contacts, an annular contact on said body surrounding said perpendicular contactor arm with which said perpendicular contactor arm is normally out of contact, and means electrically connecting said upper, lower, and annular contacts together.

2. In a switch, an insulated body, a generally horizontal contactor arm pivoted at one end on said body and having a free end, a generally perpendicular contactor arm pivoted at its upper end on the free end of said horizontal contactor arm, upper and lower fixed contacts on said body located above and below said horizontal contactor arm, resilient means acting between said body and said horizontal contactor arm serving to normally position said horizontal contactor arm in an intermediate position wherein said horizontal contactor arm is vertically spaced from and out of contact with said upper and lower contacts,

an annular contact on said body surrounding said perpendicular contactor arm with which said perpendicular contactor arm is normally out of contact, and means electrically connecting said upper, lower, and annular contacts together, said perpendicular contactor arm having a member suspended thereon below said body, said member being arranged to be swung in different lateral directions so as to engage said perpendicular contactor arm with said annular contact or elevated or depressed to engage said horizontal contactor arm with said upper or lower contacts.

5 3. In combination, a support including a frame 10 enclosing an access opening, an insulated body mounted on an upper part of said frame, said insulated body having switch means thereon including annular contact means and contactor means, said contactor means including an element 15 depending from said body, said element being movable vertically in opposite directions and laterally to engage said annular contact means and close a circuit, and a guard frame in protective relation to said access opening and 20 said support frame and secured to depend from said depending element, said guard frame being otherwise unsupported by said support and being 25 free to be raised or lowered or moved laterally with respect to the support frame to operate said 30 switch means.
